(57) **CLAIM**

The ornamental design for an infant carrier, as shown and described.

DESCRIPTION

FIG. 1 is a perspective view of an infant carrier in accordance with our new design;

FIG. 2 is a first end view thereof;

FIG. 3 is a second, opposite end view thereof;

FIG. 4 is a first side view thereof;

FIG. 5 is a second, opposite side view thereof;

FIG. 6 is a top view thereof; and,

FIG. 7 is a bottom view thereof.

The broken lines represent portions of the infant carrier that form no part of the claimed design.
